UNITED STATES PATENT OFFICE.

WILLIAM E. WINE, OF TOLEDO, OHIO.

DOOR MECHANISM FOR RAILWAY CARS.

Application filed August 19, 1925. Serial No. 51,095.

My invention relates to door mechanism for railway cars and is especially suitable for application to hopper cars although it may advantageously be employed on cars of other types.

The principal object of the invention is to provide simple and reliable door locking means which serve to support the door in partially closed as well as in fully closed position.

A further object of the invention is to provide a door locking mechanism to which power may be conveniently and efficiently applied for the purpose of forcing the door from an approximately closed position to a position of final closure.

Still another object of the invention is to provide means insuring the maintenance of the locked relation of cooperating parts when the mechanism is in service.

A primary feature of the invention consists in rotatably mounting on a hinged car door a cam member which is adapted to cooperate with a pivoted hook mounted on the car body so as to support the door either in partially closed or in fully closed position, the hook having a shoulder cooperating with said cam member for the purpose stated, means being provided for preventing an accidental unlocking rotation of said cam with respect to said hook when the door is locked in final closed position, the said cam member being adapted while in engagement with the hook to be rotated so as to press against the shoulder of the hook and thereby force the door from partially closed to fully closed position, and the axis of rotation of the cam member being disposed so as to pass between the said shoulder and the pivotal center of the hook in all positions assumed by the cam when the latter is cooperating with the said shoulder.

A further feature of the invention consists in combining a hinged door with a pivoted hook and a plurality of rotatable cam members which together serve as means for preventing the door from executing an opening movement, the cams being adapted to engage opposite sides of the hook, one of them being rotatably mounted on the door and the other being rotatably mounted on the car body and means being provided adjacent the cams for engaging the door to

limit separation of the pivotal points of the cam members.

Other features of the invention pertaining to advantageous forms of construction and combinations of parts will hereinafter appear and be pointed out in the claims.

In the drawings illustrating a preferred embodiment of the invention Figure 1 is a fragmentary side elevational view of a hopper side sheet and a swingingly mounted door showing the invention applied thereto, the door being locked in fully closed position.

Figure 2 is a sectional view on the line 2—2, Figure 1.

Figure 3 is a view corresponding to Figure 1 but showing the relation of the parts when the mechanism carried by the door initially engages the hook as the door swings toward closed position.

Figure 4 is a view corresponding to Figure 1 but illustrating the door as supported in partially closed position.

Figure 5 is a view corresponding to Figure 1 but illustrating a position assumed by the parts when the door is being forced from partially closed to fully closed position.

While the drawings illustrate a single hopper and the adjacent edge of the coacting door it is to be understood that the construction is preferably duplicated on the opposite side of the car and that the door illustrated is but one of a pair of doors connected by a spreader or stiffening member so as to swing as one.

In the drawings 1 is the sloping side sheet of a hopper and 2 is a swinging door for closing the discharge opening thereof. The door may be secured to the car body by the usual hinges (not shown) or in any desired manner and it is preferably formed from sheet metal.

Mounted upon the outer face of the door adjacent the free edge of the latter is a door spreader or stiffening member 3 which may conveniently be a bulb angle, one of its flanges being secured to the door and the other projecting outwardly therefrom. Rigidly attached to the outstanding flange of the door spreader, as by means of rivets 4, are separable members 5 and 6 respectively, forming bearings for a revoluble shaft 7 preferably extending entirely across

the car. At each end the shaft is fashioned with a cam portion 8 and terminates in a squared head 9 for receiving a wrench or other suitable tool whereby the trainman 5 may effect a rotation of the shaft 7 when the door is to be forced from partially closed to fully closed position. On opposite sides of each of its cam portions 8 the shaft is preferably provided with disks or 10 flanges 10 which by engaging the respectively adjacent door supporting hooks 11 serve to limit lateral shifting of the door with respect to the car body. The innermost flanges 10 preferably bear against the outer 15 ends of the neighboring bearing members 5 and 6, thus preventing the shaft 7 from shifting in its direction of length.

The hook 11 which cooperates with the cam member 8 carried by the door is rotatably mounted upon the car body by means 20 of a pivot rivet 12 which passes through an overlying bracket 13 and through the side sheet 1 of the hopper. This bracket may be conveniently provided on its inner side with 25 a lug 14 forming a stop for preventing undue downward swinging of the hook when the door is open. Pivots connected to the bracket, as by means of a rivet 15, is a rotatable locking cam 16 adapted to be 30 forced against the hook so as to prevent the latter from executing an unlocking rotation.

The shoulder of the hook which cooperates with the rotatable cam carried by the door is preferably curved so as to form a depression or pocket 17 adjacent the point of 35 the hook for receiving the outermost portion 18 of the cam 8, the radius of curvature of the said pocket preferably being the same as that of the cooperating face of the portion 18 40 of the cam. Adjacent the pocket 17 but nearer the pivotal point 12 the cam engaging shoulder of the hook may advantageously have a considerably greater radius of curvature. It will be perceived upon reference to 45 Figures 4 and 5 that by thus forming the shoulder of the hook the rotatable shaft carrying the cams 8 may be turned through a considerable angle while the door is supported in partially closed position before producing any substantial movement of the door 50 towards its position of final closure. The portion 19 of the cam 8 which engages the shoulder of the hook to support the door in partially closed position extends a less radial 55 distance from the axis of rotation of the cam than does the portion 18 which cooperates with the shoulder of the hook when the door is finally closed. Between these portions of different eccentricity the cam 8 is notched or 60 recessed, as at 20 for accommodating the point of the hook when the shaft 7 is being revolved in the operation of forcing the door shut. It will be observed that the axis of 65 rotation of the cam member 8 passes between 35 the shoulder of the hook 11 and its pivotal

point 12 in all positions which the cam member 8 assumes when cooperating with the shoulder of the hook, thus enabling the door to be supported in a position of partial closure requiring a minimum rotation of the shaft 7 to effect full closure of the door and thereby reducing the radial length of the portion 18 of the cam by which the final closing movement of the door is effected. It will also be noted that the pivotal center 75 12 of the hook and the hinge axis upon which the door 2 swings are disposed upon opposite sides of a line normal to the plane of the door and passing through the center of rotation of the cam member 8. This is advantageous in that the load upon the door is thus enabled to assist in preventing an accidental unlocking movement of the hook should the trainman neglect to force the locking cam 16 80 to closed position.

By preventing an unlocking movement of the hook 11 the member 16 prevents the cam member 8 from rotating to unlocked position. It will be apparent however if, as the result of the door sagging upon its hinges, the cam 8 should move downwardly away from the hook, that said cam might under such circumstances be able to assume unlocked position accidentally. To prevent such a possibility the bracket 13 is provided with an extension 21 which normally extends under the door stiffener 3 so as to engage the latter and limit sagging of the door. The upper face of the bracket extension 21 is preferably curved at its extremity so as to form a guiding face for insuring proper closing movement of the door in the event the latter has sagged greatly on its hinges. 95

In closing the door the trainman first pushes it to the partially closed position illustrated in Figure 4, the hook 11 sliding over the cam 8 and the shoulder of the hook coming into engagement with the shorter portion 19 of the cam. A wrench is then applied to the squared end 9 of the shaft and the latter is rotated in the proper direction. During a considerable portion of this rotation the door 2 is substantially unaffected, but toward the end of the rotation the portion 18 of the cam fulcrums on the shoulder of the hook 11 and forces the door to final closed position, as illustrated in Figure 1. The locking cam 16 is then forced into engagement with the hook. 105

A construction embodying the invention is advantageous not only because of its simplicity, strength and reliability, but also by reason of the fact that it enables the door to be forced to closed position with comparatively little movement of the power applying mechanism and in a most effective manner. 110

I claim:

1. In a door mechanism for railway cars, the combination with a hinged door, of a cam member rotatably mounted on said door, 115 125 130

- a pivoted hook mounted on the car body and adapted to cooperate with said cam member, said hook having a shoulder adapted to be engaged by said cam member to prevent an opening movement of said door, the axis of rotation of said cam member passing between said shoulder and the pivotal center of the hook in all positions assumed by said cam member when the latter is in engagement with said shoulder, and means for preventing an accidental unlocking rotation of said cam, said means including said hook and a member cooperating with said hook for preventing the latter from moving to unlocked position. 6. In a door mechanism for railway cars, the combination with a hinged door, of a shaft rotatably mounted on said door and provided with a cam and with a flange adjacent said cam, a pivoted hook mounted on the car body having a shoulder adapted to be engaged by said cam to retain said door in partially closed position and in fully closed position, and a rotatable cam pivotally carried on the car body adapted to engage said hook to prevent the latter from moving to unlocked position. 7. In a door mechanism for railway cars, the combination with a hinged door, of a door stiffener secured to said door adjacent the free edge thereof, said door stiffener having a flange extending outwardly from the plane of said door, a rotatable shaft provided with a cam portion, separable members secured to said outstanding flange and forming bearings for said shaft, a pivoted hook having a shoulder adapted to be engaged by said cam portion to maintain said door in partially closed position and in fully closed position, a bracket carried by the car body upon which said hook is pivotally carried, and a cam rotatably mounted on said bracket and adapted to maintain said hook in locked position. 8. In a door mechanism for railway cars, the combination with a hinged door, of a cam member rotatably mounted on said door, and a pivoted hook mounted on the car body and provided with a shoulder for engaging said cam member to maintain said door in partially closed position and in fully closed position, the pivotal center of said hook and the hinge axis of the door lying on opposite sides of a line which is normal to the plane of the door and passes through the center of rotation of said cam member. 9. In a door mechanism for railway cars, the combination with a hinged door, of a cam member rotatably mounted on said door, and a pivoted hook mounted on the car body and having a shoulder adapted to be engaged by said cam member to maintain said door in partially closed position and in fully closed position, said cam member being provided with a plurality of cam portions having different eccentricities. 10. In a door mechanism for railway cars, the combination with a hinged door, of a

the combination with a hinged door, of a cam member rotatably mounted on said door, a pivoted hook mounted on the car body and adapted to cooperate with said cam member, said hook having a curved shoulder adapted to be engaged by said cam member to prevent an opening movement of said

door, the curvature of a portion of said shoulder substantially corresponding to a portion of said cam adapted to engage therewith, and a portion of said shoulder having a different radius of curvature.

In testimony whereof I affix my signature.

WILLIAM E. WINE.
